ABSTRACT: A fencing target made of foam backed vinyl and having the form of a human being is connected to a target base with the target base being movable to a plurality of vertical positions in a support frame. The target base is provided with rollers which engage tracks on the frame, and with bolts which engage holes in the frame. An adjustable arm presenting an opponent's weapon is provided on the target base and extends outwardly therefrom for use in the practice of fencing moves.

FIG. 1.

FIG. 2.

FIG. 4

INVENTOR.
EMIL STANLEY PELLICER

SILHOUETTE FENCING TARGET WITH ADJUSTABLE ARM

This invention relates to a Silhouette Fencing Target with Adjustable Arm and springholder to hold a fencing foil, the principal object is to provide a practice target having the form of a fencer in the "On Guard" position, with its adjustable holder or arm positioned in the high line or low line, allowing the combined practice of fencing beats, counter beats against the blade of the foil held in the target's arm, followed by thrusts to the full area of the target; also allowing the practice of disengages, coupes one-twos, and other fencing moves, and constructed in such a way as to allow the use of a fencing foil.

Another use object of this target is to provide a well defined area for the landing of thrusts, this is defined by the heart placed in the upper part of the torso of the silhouette, to train the fencer in aiming with control and success.

Another use object of this target is to provide a device as specified with areas under the fencing arm and the low line (bottom of target below the waist), these areas for the training of practice thrusts needed by the sport of fencing.

A still further object of this target is to provide an adjustable arm with springholder in which a foil can be inserted and secured by its handle, against this foil aimed forward in the high or low line a series of beats and counterbeats can be practiced with the foil of the fencer using the target.

Representative embodiments of this invention are herein presented, but it will, of course, be appreciated that the invention is susceptible of incorporation in still other forms coming within the scope of the appended claims.

In The Accompanying Drawings:

FIG. 1 is a front plan view. FIG. 2 is a vertical cut side view. FIGS. 3 and 4 show details of the roller track. FIG. 5 shows details of the adjustable arm with springholder.

The silhouette is of foam 7 recovered with a vinyl-type material 2 that is tacked to a backing of plywood 8 of the same silhouette design. In turn the silhouette as described is fastened to the main board 1 with screws 11.

The adjustable arm with springholder is mounted as follows: the spring 18 is screwed on the thread of the bushing 17, the bushing 17 is then screwed on one end of the adjustable arm 16 which is a tubing cut halfway in part and held together with a bolt and wingnut 19, the opposite end of the arm 16 is screwed into the flange 15, the flange 15 is fastened with screws to the plywood backing 8. A foil 14 can be inserted and secured in the spring 18, the diameter of the spring is such that it will hold the handle of the foil firmly.

To adjust the target to the height desired or needed by the fencers using it, it can be raised or lowered vertically with the system of tracks 5 fastened with screws to the inside of the columns 4 and the rollers 6 fastened with screws to the board 1. The distance required between the two columns 4 is maintained by the rods 13 that are bolted on both sides of each column 4. The height wanted will be maintained by

pushing the pins 9 into one of the many holes provided on the inside of the columns 4.

The whole system is to be bolted to a wall using six holes 12 provided for this effect in the two columns 4. Mounted as 5 described this invention provides a practice target in the shape of the body silhouette of a right- or left-handed fencer standing in front of another fencer in the "On Guard" position. It also allows the practice of needed thrusts for the sport of fencing done with a fencing foil and in the general 10 area of the body and especially in the areas under the fencing arm and the lower line (below the waist), and the area of the heart 3 made of a strong red material glued permanently on the upper center part of the torso.

This target also provides for the practice of beats and 15 counterbeats done against the foil 14 followed by thrusts to any of the areas desired by the fencer.

This target provides for the practice of disengages, coupes, 20 one-twos, and other fencing moves and thrusts as desired by the fencer himself or the coach or teacher. All is new and novel.

I claim:

1. A silhouette fencing target comprising a support frame; a target base having a surface; foam material secured to said base over a portion of its surface; vinyl material covering said 25 foam material, said foam material being shaped to present the form of a portion of a human being in silhouette; an adjustable arm representing an opponent's weapon secured to the surface of said target base and extending outwardly therefrom, in juxtaposition to said foam material; means cooperating between said support frame and said target base for adjusting said target base relative to said frame in a plurality of vertical 30 positions; and other means for releasably securing said target base to said frame in any selected one of said vertical positions.

35. 2. The silhouette fencing target of claim 1, further comprising a member secured to said vinyl covering at a location representing the location of the heart of an opponent, said member being heart shaped.

3. The fencing target according to claim 1 wherein the 40 adjustable arm comprises a bushing portion connected to said target base and extending outwardly through said foam material, spring means connected to said bushing and a foil secured to said spring means.

45. 4. The fencing target of claim 3 wherein said means for adjusting said target base relative to said frame comprises rollers connected to said target base and a track area on said frame for receiving said rollers to permit said target base to be adjusted relative to said frame.

50. 5. The silhouette fencing target of claim 3 wherein said other means for securing said target base to said frame comprises a plurality of holes in said frame and pin means connected to said target base for placement in one of said holes for securing said target base to said frame.
